CLAIM

The ornamental design for a splicing type LED bracket light, as shown and described.

DESCRIPTION

FIG. 1 is a front elevational view of the splicing type LED bracket light;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view projecting toward the rear thereof.

The broken lines illustrate portions of the splicing type LED bracket light that form no part of the claimed design.
